BOUNCING BALL GAME APPARATUS HAVING A SOUND STRIP

Henry L. Sistrunk, Western Springs, Ill., assignor to
George H. Forsyth, Chicago, Ill.

Application August 7, 1953, Serial No. 372,985

6 Claims. (Cl. 273—30)

This invention relates to improvements in apparatus for a game of the type played with a paddle or bat and ball, and more particularly to the game of the type disclosed and claimed in Patent No. 2,629,594 issued February 24, 1953, to George H. Forsyth, comprising an apparatus including a playing court and an abutment wall wherein the main playing court is normally supported above the floor at substantially the height of an ordinary table, but wherein the ball may also rebound for play on a second court marked on the floor.

Among the features of the game apparatus of the character above described is the arrangement of the end abutment wall at a substantial angle of inclination toward the player end of the table court which insures that a ball, struck from the player end of the table court against the end abutment wall and impinging on the latter below a prescribed horizontal boundary line, will tend to be deflected downwardly on rebound so as to bounce on the surface of the main table court before it reaches the player end of the latter, but wherein also the abutment wall is extended above the aforesaid horizontal boundary line so that a ball, impelled with sufficient force from the player end of the table court and impinging on the end abutment wall above said boundary line, can be rebounded so as to clear the end of the table court and strike directly on the floor court.

Among the objects of the present invention is to provide an improved form of game apparatus of the character described wherein a portion of the abutment wall above the horizontal boundary line is inclined toward the player position end of the table court at an angle slightly less than the portion below said boundary line, so as to provide what may be termed a "smash" playing area, against which any ball must be struck with sufficient force to clear the player end of the table court; otherwise, the player who strikes the ball commits a "fault" and loses a point in the game.

A further object of the invention is to provide a secondary playing area immediately above the horizontal boundary line with a rebounding area having substantially the same resilient characteristics as the primary playing area below said boundary line but having sound characteristics distinctly different from that of said primary playing area when struck by a ball, in order to apprise the players in doubtful instances whether or not the ball has struck the end abutment wall above or below the boundary line.

Other objects and advantages of the invention will appear from time to time as the following description proceeds.

The invention may best be understood by reference to the accompanying drawings, in which:

Figure 1 is a perspective view showing one form of game apparatus made in accordance with my invention;

Figure 2 is an enlarged vertical section of the game apparatus shown in Figure 1, taken longitudinally of the table court thereof;

Figure 3 is an enlarged detail of the changed sound-

2

producing means associated with the horizontal boundary line on the end abutment wall of the table;

Figure 4 is a fragmentary perspective view showing a variant form of end abutment wall to which the sound-producing means may be applied.

Referring now to details of the embodiment of my invention as applied to the game apparatus shown in Figures 1, 2 and 3, said game apparatus, indicated generally at 10, includes a playing court, indicated generally at 11, a forwardly inclined end abutment wall 12, and two upright side walls 13, 13 diverging slightly from the opposite sides of the end abutment wall and terminating short of the front or player position end of the playing court 11. In the illustrative form shown in Figures 1 and 2, the playing court 11 is made up of a rear court section 14 inclined downwardly from the end abutment wall 12 at a slight angle to the horizontal for approximately two-thirds of the length of the playing court, and a contiguous front court section 15 inclined upwardly at approximately the same angle to the horizontal for the remaining one-third of the length of the playing court. It will be understood, however, that the horizontal disposition of the playing court may be varied within reasonable limits, provided that it conforms to the basic relationship between the height and angle of forward inclination of a lower portion of the abutment wall 12 and the horizontal length of the court, which relationship is essential to the game, as will now be described.

The end abutment wall 12 has a horizontal boundary line 16 demarcated along its playing face to define a primary playing area 17 below said line and a secondary playing area 18 above said line which playing areas have substantially the same surface resilience. The arrangement is such that a plane intersecting said end panel at right angles thereto along said boundary line, as indicated by the dotted line A—A in Figure 2, will also pass through the far or player position end of the playing court substantially at the base line 19 thereof. This arrangement, which constitutes a basic feature of the game apparatus of the kind to which the present invention is directed, insures that any ball directed toward the end panel from the opposite or playing end of the court, and striking the primary playing area 17 below the horizontal boundary line 16, will always be rebounded initially toward the table court surface, short of the base line 19 thereof. In other words, it makes it impossible for a player to rebound a ball from the primary playing area 17 so as to clear the table court 11 on the fly.

On the other hand, in accordance with certain rules of the game, it is permissible for a player to strike or rebound a ball from the end abutment wall above the boundary line (known as a "smash" shot) only upon condition that the ball be struck with sufficient force that it clears the base line 19 of the table court on the fly, and also bounces within the boundaries of the floor court area, indicated at 20 in Figure 1. Should he fail, with such a "smash" shot, to clear the base line 19 of the table court on the fly upon rebound from the secondary playing area 18 (or the ball fails to alight within the floor court area), he gets a "fault" and loses a point on the score.

Accordingly, in playing the game under the above-mentioned rules, the secondary playing area 18 above the boundary line 16 is preferably disposed at a slightly less angle of inclination to the table court than the primary playing area 17 on the end abutment wall. Without this change in inclination of the secondary playing area 18, it would be practically impossible, for even expert players, to clear the table court with a "smash" shot when rebounding from near the lower edge of the secondary area 18, because of gravitational effect on the ball in flight.

It also becomes of paramount importance in a fast game of this kind that each player be apprised instantly in doubt-

ful cases whether his opponent may be attempting a "smash" shot by striking the ball against the abutment wall above the horizontal boundary line 16, so that the player can know when to step back quickly should it be necessary for him to return the ball from the floor court rather than from the table court. It is also important, for scoring purposes of course, that players be apprised in doubtful cases whether the ball has struck below the boundary line during play.

Referring now more particularly to the novel features of the present invention, it will be seen from Figures 1, 2 and 3 that I provide a horizontally disposed strip 21 embedded in the upper secondary playing area 18, having its bottom edge coincident with the boundary line 16. Said strip is made of a material having substantially the same resilience, but having distinctly different sound characteristics when struck by a ball, in comparison with the material used for the adjacent playing areas 17 and 18 below and above the strip 21, respectively.

For illustrative purposes, it may be assumed that both the playing surfaces 17 and 18 on the end panel is made of a single sheet of plywood, while the strip 21 may be made of sheet metal, plastic or other material, having inwardly turned flanges 22, 22 embedded in the surface of the end panel, and with the upper and lower edges of the strip flush with the meeting faces of the two playing areas 17 and 18. The portion 23 of the panel forming playing area 18 underlying the strip 21 may be recessed to a depth slightly more than the thickness of said strip so as to provide a shallow open space 24 between the inner surface of the strip and the opposed face of said panel, as shown in Figure 3, so as to insure a more distinctive difference in sound when the strip is struck by a ball.

Since the sound strip 21 preferably has substantially the same resilience for rebound of the ball as the two adjacent playing areas 17 and 18, the proper thickness of the strip and depth of the shallow recess 24 (if the latter is used), can be determined experimentally, depending upon the nature and physical characteristics of the material from which the strip is made.

The strip 21 is disposed entirely above the boundary line 16 rather than below it, because most of the play is usually confined to the primary playing surface 17 below the boundary line, and it is only when one of the players attempts a "smash" shot above the boundary line that the opponent should be alerted to the possibility of such an attempt.

The sound strip 21 should be of sufficient height to eliminate any reasonable question in doubtful cases whether the ball has been struck above or below the boundary line 16 at the bottom edge of said strip. In practice, a strip of about three inches wide has given satisfactory results. Although a player can usually observe whether the ball strikes the abutment wall well above the boundary line, it is often difficult, if not impossible, to be certain, one way or the other, when the ball strikes near the boundary line, without the aid of a difference in sound as a guide for the play, and scoring of the game.

The upper edges of the side walls 13, 13 preferably extend vertically only to the boundary line 16, so that a player making a "smash" shot will derive no advantage from rebounding against either side wall.

Figure 4 shows a variant form of game apparatus to which my invention is equally applicable, wherein the end abutment wall 12a, corresponding generally to the inclined abutment wall of Figures 1 and 2, consists of two panels 12b, 12b of equal size, meeting each other at a wide dihedral angle along the longitudinal center line of the apparatus, and are extended at more upright angles above the boundary line 16a. A sound strip 21a extends horizontally across both of the panels 12b, 12b, above the boundary line 16a, corresponding to the boundary line 16 of Figures 1 and 2.

Although I have shown and described certain embodi-

ments of my invention, it will be understood that I do not wish to be limited to the exact construction shown and described, but that various changes and modifications may be made without departing from the spirit and scope of the invention as defined in the appended claims.

I claim:

1. In a bouncing ball game apparatus having an elongated table court and an abutment wall projecting upwardly at one end thereof to provide an unobstructed ball-rebounding surface inclined at an acute angle to said table court, said abutment wall having a generally horizontal boundary line thereacross to define upper and lower rebounding areas having substantially the same surface resilience, the relative length of the table court and the height and angle of said lower rebounding area being such that a line extending from the player position end of the table court to said boundary line is normal to the plane of the lower rebounding area, whereby a ball struck from the player position end of the court and impinging said lower rebounding area will rebound initially toward the table court short of the player position end of the latter, and a strip of material extending horizontally across said upper ball-rebounding area with its lower edge coincident with said horizontal boundary line and with its outer face substantially flush with the proximate surface of said upper rebounding area, said strip being of substantially the same resilience as that of the ball-rebounding areas but having distinctly different sound characteristics than said areas upon being struck by a ball.

2. The structure in accordance with claim 1, wherein said horizontal strip consists of a piece of sheet material with inturned marginal flanges embedded in the upper ball-rebounding area.

3. The structure in accordance with claim 2, wherein the ball-rebounding area underlying the horizontal strip is recessed in spaced relation from the inner face of the strip.

4. In a bouncing ball game apparatus having an elongated table court and an abutment wall projecting angularly upwardly at one end thereof to provide an unobstructed ball-rebounding surface for said table court, said abutment wall having a generally horizontal boundary line thereacross to define upper and lower rebounding areas having substantially the same surface resilience, the relative length of the table court and the height and angle of inclination of said lower rebounding area being such that a line extending from the player position end of the table court to said boundary line is normal to the plane of the lower rebounding area, whereby a ball struck from the player position end of the court and impinging said lower rebounding area will rebound initially toward the court short of the player position end of the latter, and the rebounding area above said boundary line being disposed at a greater angle of inclination to the table court than that of the lower rebounding area.

5. In a bouncing ball game apparatus having an elongated table court and an abutment wall projecting angularly upwardly at one end thereof to provide an unobstructed ball-rebounding surface for said table court, said abutment wall having a generally horizontal boundary line thereacross to define upper and lower rebounding areas having substantially the same surface resilience, the relative length of the table court and the height and angle of inclination of said lower rebounding area being such that a line extending from a player position end of the table court to said boundary line is normal to the plane of the lower rebounding area, whereby a ball struck from the player position end of the court and impinging said lower rebounding area will rebound initially toward the court short of the player position end of the latter, the rebounding area above said boundary line being disposed at a greater angle of inclination to the table court than that of the lower rebounding area, and a strip of material embedded in and extending horizontally across said upper ball-rebounding area, said strip having the lower edge thereof coincident with said horizontal boundary

line and with the upper and lower edges of the strip being substantially flush with the proximate surface of said upper rebounding area, said strip being of substantially the same resilience as that of the ball-rebounding areas but having distinctly different sound characteristics than said areas upon being struck by a ball.

6. In a bouncing ball game apparatus having an elongated table court and an abutment wall projecting angularly upwardly at one end thereof to provide an unobstructed ball-rebounding surface for said table court, said abutment wall having a generally horizontal boundary line thereacross to define upper and lower rebounding areas having substantially the same surface resilience, the relative length of the table court and the height and angle of inclination of said lower rebounding area being such that a line extending from a player position end of the table court to said boundary line is normal to the plane of the lower rebounding area, whereby a ball struck from the player position end of the court and impinging said

lower rebounding area must rebound initially toward the court short of the player position end thereof, the improvement comprising, the upper rebounding area being disposed at a greater angle of inclination to the table court than the angle of inclination of the lower rebounding area, whereby a ball struck with sufficient force from the player position end of the court and impinging said upper rebounding area can rebound beyond the player position end of the court.
